W. H. NICHOLAS

DUSTPAN

Filed March 24, 1924

UNITED STATES PATENT OFFICE.

WILBUR H. NICHOLAS, OF INDIANAPOLIS, INDIANA.

DUSTPAN.

Application filed March 24, 1924. Serial No. 701,362.

To all whom it may concern:

Be it known that I, WILBUR H. NICHOLAS, a citizen of the United States, residing at Indianapolis, in the county of Marion and 5 State of Indiana, have invented new and useful Improvements in Dustpans, of which the following is a specification.

The object of this invention is to provide a durable, efficient and inexpensively 10 constructed dust pan with a long handle such that the pan can be manipulated on a floor by a person without stooping down.

Another object is to provide means for 15 adjusting the angle of the handle with relation to the pan, and for clamping it at a given angular position in use, or for suspension from a nail against the wall where the pan may serve as a receptacle for a dust cloth or for other articles when the 20 pan is not in use.

A further object is to provide resilient 25 means for holding the front edge of the pan in contact with the floor by foot pressure of the user, to keep sweepings from going under the pan; and an additional object is to easily dismember the parts for compact nesting of the pan, for storage and shipment.

I accomplish the above, and other objects 30 which will hereinafter appear, by the means illustrated in the accompanying drawing in which—

Fig. 1 is the flat sheet from which the pan is formed. Fig. 2 is a top plan view of 35 the pan as formed from said flat sheet. Fig. 3 is a perspective view of the pan with handle and other members in complete assembly. Fig. 4 is a vertical central section of the assembly shown in Fig. 3. Fig. 5 is a perspective view of the handle 40 rod. Fig. 6 is a perspective view of the metal strap reenforcing member, and Fig. 7 is a perspective view of the bolt and nut.

Like characters of reference indicate like 45 parts in the several views of the drawing.

In the metal sheet 8, Fig. 1, the triangular portions outside of the dotted lines 50 $a-b$, are bent up at an acute angle on said lines $a-b$, and the triangular members are curved in the manner shown to lap an edge $b-c$ of one under the corresponding edge of the other. The edge $b-b$, and the two edges $b-c$, are bent outwardly on the adjacent dotted lines to stiffen said edges.

A slot is punched through the metal at $a-a$ for the passage of a metal strap 9, preferably of steel. A tongue 10, is formed in the adjacent margin by cuts 11, 11, and this tongue is bent upon the lapped edges 60 $b-c$ to hold them in their lapped relation to each other. A hole 12, is punched near the outer end of each edge $b-c$, such that the two holes register with each other when the edges are brought together in said 65 lapped relation.

A handle 13, is a heavy wire or rod of metal with a laterally disposed coil 14, of several turns near one end, the extreme end portion extending tangentially to form a 70 stop-finger 15. A loop 16, at the other end of the handle 13, affords a hand hold when the pan is used, and as a loop to hang the pan by when it is not in use as a dust 75 pan.

The metal strap 9, has that part which is passed out through the slot $a-a$, bent to form a foot 17, and a U-shaped loop is formed on the opposite upper end of the strap of a size and shape to receive the coil 80 14 with a close fit. The metal strap 9, has a round bolt hole 18 and also a square hole 19 in its adjacent bent member, to receive a bolt 20. The squared hole 19 receives a usual squared portion of the bolt 85 next the bolt head, and a wing nut 21 is screwed on the threaded end of the bolt.

The complete assembly is shown in Figs. 3 and 4, wherein it is observed that the bolt 20 passes through the two holes in the strap 90 and also through the two holes 12, of the pan, and the nut 21 holds the assembly. It will also be apparent that by screwing down the nut the members of the U-bend in the strap are brought closer together, thereby 95 forming a clamp which will more or less tightly grip the coil 14. By tightening this construction which constitutes a clamp, the coil may be held at any angular position of the handle 13 relative to the pan, except 100 when contact of the finger 15 with the pan limits the adjustment. Also, by running the wing nut off and then removing its bolt, the strap and the handle are readily removable from the pan and each from the other, as is done for convenience in storage and 105 shipments. The pointed end of one pan may be inserted into the next pan for nesting compactly on such occasions.

Having thus fully described the best form 110

of my invention now known to me, what I claim as new and desire to secure by Letters Patent, is:—

1. A dust pan formed out of a rectangular metal sheet having two opposite corners on a long side of the sheet bent in the same direction at angles on lines extending from opposite corners of the sheet approximately to the middle of the edge between the two corners, said corners being curved toward each other until their edges lap, a tongue at the convergence of the angular bends of the corners bent upon the adjacent laps of the corners to aid in locking them in their lapped relation, a handle having an extension, and means for securing the handle to the pan comprising a strap attached to the pan having means cooperating with the handle extension, a bolt which passes through the lapped portions near the upper edges of the bent corners and securing the handle extension to the strap means.
2. A sheet metal dust pan having a bottom and a rear wall with a slot through the bottom near the wall and bolt holes through the wall near its upper edge, a metal strap passing through the slot and projecting outside of the pan and terminating at its upper end with a U-shaped loop, a handle having a lateral extension fitting in the loop of the strap, a bolt passing through the two stems of the loop and through the wall of the pan, and a nut on the bolt to regulate the tension of the loop on the handle extension to frictionally hold a given position of the handle.
3. A sheet metal dust pan having a bottom and a rear wall, said bottom having a slot near the wall and said wall having upper edge bolt holes, a metal strap contact-

ing the inner wall from the bolt holes to the slot and passing out through the slot and projecting therebeyond, said strap having a U-shaped loop at its upper end, a handle rod having a lateral cylindrical projection formed by a series of coils of the rod, said coils terminating in a finger and said cylindrical coils fitting in the U-shaped loop of the strap, a bolt passing through the bolt holes in the pan and through both arms of the loop, and a nut on the bolt to clamp the strap to the wall of the pan, and the loop to the cylinder of the handle.

4. In a dust pan, a pan-body member, a spring-bar normally holding the rear of the pan away from the floor, an end of the bar being bent to form a spring-opening clamp, a handle having a spring-coil entering the clamp to attach the handle to the pan, said coil having a stop to contact the pan, and means for closing the clamp on the coil.

5. The combination, with a dust-pan, of a spring-strap rigidly attached to the pan and extending rearwardly of the pan into contact with the floor and normally elevating the rear end of the pan, said strap being adapted to be pressed downwardly by the foot of the user to force the front edge of the pan into contact with the floor, said bar having a loop at its upper end, a handle having a member entering the loop to form a hinge attachment between the bar and handle, and means for clamping the loop to the hinge attachment of the handle to retain any given angular relation between the handle and loop.

Signed at Indianapolis, Indiana, this the 21st day of March, 1924.

WILBUR H. NICHOLAS.
